UNITED STATES PATENT OFFICE.

RUSSELL H. WILHELM, OF EASTON, PENNSYLVANIA, ASSIGNOR TO INGERSOLL-RAND COMPANY, OF JERSEY CITY, NEW JERSEY, A CORPORATION OF NEW JERSEY.

ROCK DRILL.

Application filed April 22, 1926. Serial No. 103,855.

This invention relates to rock drills, but more particularly to a distributing valve for fluid actuated rock drills.

The objects of the invention are to obtain 5 a quick and positive valve action by utilizing the exhaust pressure fluid from the cylinder for throwing the valve.

Other objects will be in part obvious and in part pointed out hereinafter.

10 The invention consists of the combination of elements and arrangement of parts substantially as hereinafter described and more particularly pointed out in the appended claims and illustrated in the accompanying 15 drawings, in which

Figure 1 is a longitudinal sectional elevation of a portion of a rock drill showing the valve in position for admitting pressure fluid into the rearward end of the cylinder 20 for impelling the piston forwardly,

Figure 2 is a view similar to Figure 1 showing the valve in position to admit pressure fluid to the front end of the cylinder 25 for returning the piston, and Figure 3 is a detail view of the inner end of the valve bushings.

Referring to the drawings, the invention is shown embodied in a rock drill having a cylinder A in which is arranged a reciprocating piston B. The piston B in this instance is provided with a forwardly extending nose D cooperating slidably with a front cylinder washer E which forms a closure for the front end of the cylinder A. A closure 30 for the rearward end of the cylinder A is in this instance provided in the form of a back cylinder washer F which also forms an abutment for a rotation ratchet G and is bored as at H for the reception of a rifle bar J. The rifle bar J interlocks slidably with a rifle nut K carried by the piston B in the rearward end of said piston. A ratchet head L preferably formed integrally with the rifle bar carries suitable pawl devices O which 35 operate with the rotation ratchet G in a well known manner for holding the rifle bar stationary during one of the strokes of the piston and for permitting the rifle bar to rotate with the piston during the other stroke 40 of the piston.

At the rearward end of the cylinder A is arranged a back head P having a recess Q for the reception of the rotation ratchet G and to cooperate with the back cylinder washer F for centralizing the back head P

with respect to the cylinder A. The back head P may be of the type usually provided for hand held tools as indicated in the drawings, although not necessarily so, since the invention is not limited in its use to any particular type of drill. A washer R may be inserted in the rearward end of the recess Q to form an abutment for the rotation ratchet G and ratchet head L and is bored to receive a portion of the rifle bar J for maintaining 60 said rifle bar centrally with respect to the rotation ratchet and other parts wherewith it cooperates.

Disposed on the cylinder A, and preferably longitudinally thereof as illustrated, is 70 a valve chest S having a chamber T formed therethrough. The chamber T is preferably of substantially the same diameter throughout its length and may be recessed at its ends as at U and V to receive flanges W and X of 75 valve bushings Y and Z. The valve bushings Y and Z are inserted in opposite ends of the chamber T and may be held against endwise movement by any suitable means. In the present instance this is accomplished by 80 means of bolts b and nuts c which may be arranged on opposite sides of the valve chest S to clamp plates d firmly against the ends of the bushings Y and Z.

To the end that the bushings Y and Z may 85 be held against rotation within the chamber T, pins e are inserted in the flanges of the bushings to cooperate with suitable slots f formed in the valve chest S.

In accordance with the present invention, 90 a pressure actuated valve g is arranged in the bushings Y and Z for distributing the pressure fluid to the ends of the cylinder. The valve g is provided with a hollow bore h which extends throughout the length of the 95 valve thus making the valve tubular in form. The pressure fluid distributed by the valve may be conveyed to the chest through a connection j preferably formed at one end of the valve chest S and communicating with the bore h of the valve through a recess k formed near the outer end of the bushing Z.

It will be noted that the interior or bore h of the valve is at all times exposed to live 105 pressure fluid as are also the ends of the valve. In the present instance the pressure fluid to the ends of the cylinder may pass through radial ports o and p and passages q and r to the rearward and front ends respectively of the cylinder. Suitable exhaust ports s and t 110

are formed between the cylinder A and the valve chamber T for exhausting the pressure fluid from the front and rearward ends of the cylinder into the chamber T. The pressure fluid thus exhausted from the cylinder may pass to the atmosphere through a main exhaust port *u*, preferably leading from the central portion of the chamber T. A central flange *v* carried by the valve *g* may reciprocate between the inner ends *Y'* and *Z'* of the bushings *Y* and *Z* for the purpose of establishing communication between the exhaust passages *s* and *t* and the main exhaust port *u*.

In order that a considerable area of the side of the flanges *v* may be exposed to the exhaust pressure fluid from the exhaust passages *s* and *t*, the inner ends of the bushings *Y* and *Z* may be relieved or undercut as at *u*.

In the present instance the bushings *Y* and *Z* are provided with annular grooves *x* and *y*, preferably located between the inlet passages *r* and *q* and the exhaust passages *s* and *t*. The annular grooves *x* and *y* are so positioned that when the valve *g* is in one of its limiting positions, the grooves may register with the radial ports in the valve.

Leading from the annular groove *x* is a longitudinal passage *z* of suitable cross sectional area and so positioned that pressure fluid issuing therefrom will be directed against the forward face of the flange *v* of the valve. A similar passage *2* leading from the groove *y* is formed in the bushing *Z* to direct a stream of pressure fluid against the opposite face of the flange *v* when the valve is thrown forwardly to the position indicated in Figure 2.

In the operation of the device, with the valve *g* and the piston B in the positions indicated in Figure 1, pressure fluid entering the inlet connection *j* and the recess *k* will pass into the bore *h* of the valve and thence through the radial ports *o* and the passage *q* to the rearward end of the cylinder A to impel the piston forwardly. As the piston proceeds in a forwardly direction the air in the forward end of the cylinder may escape through the exhaust passage *s* and through the valve chamber and the main exhaust port *u* to the atmosphere. After the exhaust passage *s* has been covered by the piston B, the air remaining in the front end of the cylinder will be compressed by the piston. At about the time the piston B reaches its forward limiting position, the exhaust port *t* will be uncovered by the piston and the pressure fluid utilized for impelling the piston forwardly will pass through the exhaust passage *t* and acting against the rearward face of the flange *v* of the valve will throw the valve forwardly to the position illustrated in Figure 2. It will thus be seen that a clear path is established between the rearward end of the cylinder and the atmosphere for the escape of exhaust pressure fluid.

During the forward movement of the piston B and while the valve is still in the position in Figure 1, the radial port *p* will be in registry with the annular groove *x*. In this position of the valve, pressure fluid will flow through these channels and through the passage *z* to act against the forward face of the flange *v* for holding the valve firmly against the inner face of the bushing *Z*.

After the valve has been thrown forwardly to the position shown in Figure 2, the radial ports *p* will be moved into registry with the inlet port *r* and pressure fluid will flow to the front end of the cylinder for returning the piston. In this position of the valve the radial ports *o* will register with the annular port *y* and pressure fluid will be admitted through the passage *2* to act against the rearward face of the flange *v* for holding the valve in its forward limiting position. The valve *g* will thus be held against the bushing *Y* until the piston B has overrun the exhaust passage *s*. The pressure fluid utilized for impelling the piston rearwardly may then pass into the valve chamber T to act against the front face of the flange *v* for throwing the valve rearwardly to the position illustrated in Figure 1, thus completing the cycle of operations.

The foregoing described valve has been found to function in an unusually efficient manner. It is quick and positive in its action and of simple and inexpensive construction. The efficiency of the valve is due, in a large measure, to the manner in which the exhaust pressure fluid is utilized for throwing the valve and, in part, to the fact that after the valve has been thrown to its limiting position, a stream of live pressure fluid acts constantly against the flange for holding the valve in thrown position.

I claim:

1. In a rock drill, the combination of a cylinder, a piston in the cylinder, a valve chest having a chamber and a main exhaust port, said valve chest having inlet and exhaust passages leading to the cylinder, a pressure actuated valve in the chamber to control the inlet and exhaust passages, said valve being hollow throughout its length and constantly exposed to live pressure fluid of equal pressures at its ends, and a flange on the valve exposed to pressure fluid from the cylinder for throwing the valve.

2. In a rock drill, the combination of a cylinder, a piston in the cylinder, a valve chest having a chamber and a main exhaust port, said valve chest having inlet and exhaust passages leading to the cylinder, a tubular valve in the chamber through which pressure fluid passes and having ports to register with the inlet passages for admitting pressure fluid to the cylinder for actuating the piston, and a flange on the valve controlling communication between the exhaust

port and the exhaust passages and against which exhaust pressure fluid from the cylinder acts to throw the valve.

3. In a rock drill, the combination of a cylinder, a piston in the cylinder, a valve chest having a chamber and a main exhaust port, said valve chest having inlet and exhaust passages leading to the cylinder, a tubular valve in the chamber constantly exposed interiorly and at its ends to live pressure fluid and having radial ports to register with the inlet passages, and a central flange on the valve exposed to exhaust pressure fluid from the cylinder whereby the valve is thrown, said valve chest having annular grooves to register with the radial ports, and passages leading from the annular grooves to the exhaust passages for directing pressure fluid against the flange to hold the valve in thrown position.

4. In a rock drill, the combination of a

cylinder, a piston in the cylinder, a valve chest having a chamber and a main exhaust port, said valve chest having inlet and exhaust passages leading to the cylinder, a tubular valve in the chamber constantly exposed interiorly and at its ends to live pressure fluid and having radial ports to register with the inlet passages, and a central flange on the valve exposed to exhaust pressure fluid from the cylinder whereby the valve is thrown, said valve chest having annular grooves between the inlet and exhaust passages to register with the radial ports, and longitudinal passages leading from the annular grooves to the exhaust passages for directing pressure fluid against the flange to hold the valve in thrown position.

In testimony whereof I have signed this specification.

RUSSELL H. WILHELM.
